(57) **CLAIM**

The ornamental design for a putter head, as shown and described.

DESCRIPTION

FIG. 1 is a top perspective view of a first embodiment putter head showing my new design;

FIG. 2 is a top plan view of the first embodiment putter head; and,

FIG. 3 is a top perspective view of a second embodiment putter head showing my new design.

The broken line showing is for illustrative purposes only and forms no part of the claimed design.

1 Claim, 2 Drawing Sheets**FIG. 1****FIG. 2**

FIG. 3
